GUN MOUNTING FOR SUBMARINES.

Application filed June 4, 1923. Serial No. 643,161.

To all whom it may concern:

Be it known that I, LAWRENCE Y. SPEAR, a citizen of the United States, residing at New London, in the county of New London,

5 State of Connecticut, have invented certain new and useful Improvements in Gun Mountings for Submarines; and I do hereby declare the following to be a full, clear, and exact description of the invention, such as 10 will enable others skilled in the art to which it appertains to make and use the same.

This invention relates to gun mountings for submarines, the principal object being to provide a mounting such that the gun may 15 be trained and operated with maximum efficiency while the entire submarine, with the exception of the conning tower, is submerged. In general, this object is accomplished by providing a non-recoil gun on the 20 conning tower, and mounting the gun so that it may be raised or lowered as desired. This invention makes it possible to use a larger gun than is commonly employed, and the effectiveness of the submarine is greatly 25 increased by virtue of the increased height of the gun above the deck.

The ordinary practice in mounting a gun on a submarine, is to place the gun on the deck in front of the conning tower. When 30 the gun is in use, the upper portion of the submarine must be exposed in order to make it possible to reload the gun from the deck and to raise the gun above the surface of the water to the required height. Furthermore, 35 it is practically impossible to reload the ordinary deck gun when the weather is rough. It is thus apparent that the ordinary practice of mounting a standard gun on the deck of a submarine is open to a number of objections, the most important of which are the 40 relatively large area exposed to vertical and horizontal fire due to the fact that the conning tower and a large portion of the deck are exposed when the submarine is in the 45 firing position; the considerable time required to pass from submerged to firing position and from firing to submerged position, due to the fact that a large part of the submarine must be raised above the water or 50 submerged as the case may be; and the limited height to which the gun may be raised above the water level. Owing to the weight and recoil of the standard guns usually employed, it is not possible to mount 55 such a gun very far above the deck.

I have found that the disadvantages of the ordinary gun-mounting for submarines may be entirely avoided by employing a non-recoil gun and mounting it on the conning tower in such a manner that the gun may be 60 raised and lowered as desired. By using a non-recoil gun of any suitable type, it is possible to mount the gun at considerable distance above the deck of the submarine without subjecting the gun-support and associated parts to excessive stresses when the gun is fired. Therefore, I prefer to mount the gun on the conning tower or on the top of a water-tight trunk, and to provide means whereby the gun may be raised considerably 70 above the top of the conning tower. With the gun mounted in this manner, it is possible to raise the gun approximately twice as high as the maximum elevation or height of the ordinary deck gun, without exposing to 75 gun fire any greater portion of the submarine; and it is possible to operate the gun at the usual elevation above the water without exposing any part of the submarine except 80 the conning tower.

The various objects and advantages of this invention will be apparent upon considering the following detailed description, which is to be taken in conjunction with the accompanying drawings, in which:

Fig. 1 is a diagrammatic longitudinal section of a submarine conning tower provided with the improved gun-mounting;

Fig. 2 is a top plan view of the submarine conning tower shown in Fig. 1.

In Figs. 1 and 2 of the drawing, 1 indicates the deck of a submarine and 2 the conning tower surmounted by the spray shield 3. The clearing lines 4 extend lengthwise of the submarine above the spray shield 3 and clear the periscopes 5 and all other accessory devices associated with the conning tower, except when such devices are raised to their uppermost positions.

A non-recoil gun 6 having a reaction or recoil compensating device 12 thereon is mounted on the conning tower. This gun may be any suitable type of non-recoil gun which automatically compensates, to a greater or less degree, for the reaction caused by the firing of the projectile. Other things being equal, the most satisfactory type of non-recoil gun is that which neutralizes the reaction of the projectile to the greatest degree. The type of non-recoil gun shown in 110

the accompanying drawing and which I prefer to employ is that type of gun which does not have to be withdrawn into a water-tight compartment when the vessel is submerged. The preferred embodiment of my invention contemplates the use of an exposed non-recoil gun, as distinguished from a gun wholly or partially stored within a water-tight compartment except when in its 10 firing position.

I prefer to employ a pneumatic hoist 7 for raising and lowering the gun 6. The drawing shows a diagrammatic representation of a pneumatic hoist comprising a well 15 or casing 8 and a plunger 9 adapted to telescope within the casing. The plunger 9 may be raised or lowered by regulating the supply of compressed air to the casing 8 in any well-known manner. The plunger 9 20 carries a gun support 10, shown in the form of a yoke, which carries the trunnions 11 of the gun.

A platform or bench 13 is provided on the plunger 9 near the gun support 10, and 25 serves as a support for the gunner when he reloads the gun. The platform 13 is preferably fixed to the support 10 so as to rotate with the gun when it is turned about the vertical axis through its support. This 30 turning operation may be performed by the gunner on the platform 13 in any convenient manner, as by means of a hand wheel 14. The platform may be provided with an extension 15 enabling the gunner 35 to stand back of the gun when reloading it.

The ammunition may be raised to the top of the conning tower 2 by means of an ammunition hoist 16. As shown in the drawing, this hoist may consist of an inclined 40 tube containing a chain or other suitable conveyer 17 operated by any convenient means, such as the motor 18. The ammunition is placed in the lower end of the tube and the conveyer 17 carries it to the top of the tube where it displaces a hinged cover 19 and is discharged onto the top of the conning tower. The ammunition may be temporarily stored in convenient receptacles 20, ready to be handed to the gunner 45 on the platform 13. The platform 13 is preferably provided with a number of openings 21 which receive the shells 22 on the conning tower when the gun 6 and platform 13 are lowered to the position shown in dotted lines in Fig. 1.

This invention makes it possible to mount a relatively large-sized gun, on the conning tower of a submarine, without greatly increasing the weight of, or complicating the 60 arrangement of the several parts comprising the conning tower, and associated therewith. By providing a pneumatic hoist for the gun, it is possible to raise and lower the gun very rapidly; and the platform 13 makes it possible 65 to operate the gun more effectively

than the ordinary deck gun can be operated. The platform 13 is protected to a considerable extent by the spray-shield 3. This spray shield not only protects the platform 13, but it also serves as a fair-water for the 70 gun in its lowered position as well as for the compass binnacle, periscope supports, and such other fittings or appliances as may be necessarily or conveniently located above the top of the conning tower. The ammunition may readily be supplied to the platform 13, and the gun may be reloaded in the most efficient manner.

The importance of having the non-recoil gun mounted on the conning tower and 80 having means for raising this gun high above the clearing lines is apparent when consideration is given to the fact that a submarine, provided with such a gun-mounting, may be passed from submerged to 85 firing position in approximately one-thirty-fifth of the time required to raise a submarine, equipped with an ordinary deck gun, from submerged to firing position. Furthermore, by means of this invention, 90 the gun may be raised to the usual elevation above the water without exposing any portion of the submarine except the conning tower and, if it is so desired, this tower 95 may be armored. When a submarine equipped with an ordinary deck gun is in its firing position, the greater portion of the deck and all of the conning tower must be exposed to gun fire.

It is to be understood that this invention 100 is not limited to the particular embodiment herein described, and shown diagrammatically in the drawings, but includes such modifications as fall within the scope of the appended claims. While I prefer to construct the spray shield 3 so that it extends 105 well above the top of the conning tower to protect the platform 13 and associated parts, especially when the gun and platform are in their lowered position, and to form 110 a fair-water for reducing the resistance of the lowered gun to a negligible quantity; yet this feature, as well as various other features of the invention may be varied, or in 115 some instances even eliminated, without departing from the scope of the invention.

I claim:

1. The gun mounting for submarines, comprising the combination with the conning tower of a submarine, of an exposed gun 120 supported by the conning tower above the deck of the submarine, said gun having means associated therewith for neutralizing substantially all of the reaction due to firing a projectile from the gun, whereby the conning tower is not subjected to the greater 125 part of the force of reaction of the gun.

2. The gun mounting for submarines, comprising the combination with the conning tower of a submarine, of an exposed 130

- gun supported by and arranged above the conning tower, said gun having means associated therewith for neutralizing substantially all of the reaction due to firing a projectile from the gun, whereby the conning tower is not subjected to the greater part of the force of reaction of the gun. 5
3. The gun mounting for submarines, comprising the combination with the conning tower of a submarine, of an exposed gun arranged above the conning tower, and means for raising or lowering said gun, said gun having means associated therewith for neutralizing substantially all of the reaction due to firing a projectile from the gun, whereby the conning tower is not subjected to the greater part of the force of reaction of the gun. 10
- 10 4. The gun mounting for submarines, comprising the combination with the conning tower of a submarine, of a non-recoil gun associated with the conning tower, means for raising the gun above the top of the conning tower, and means for supplying ammunition to the top of the conning tower. 15
- 20 5. The gun mounting for submarines, comprising the combination with the conning tower of a submarine, of a non-recoil gun associated with the conning tower, means associated with the conning tower for raising the gun above the top of the conning tower, a platform fixed with respect to the gun, and means for rotating the gun and platform about a substantially vertical axis. 25
- 30 6. The gun mounting for submarines, comprising the combination with the conning tower of a submarine, of a gun arranged above the top of the conning tower, hoisting means associated with the conning tower for raising and lowering the gun, means for hoisting ammunition to the top of the conning tower, and a platform arranged above the top of the conning tower and fixed with respect to the gun. 35
- 40 7. The gun mounting for submarines, comprising the combination with the conning tower of a submarine, of a gun arranged above the top of the conning tower, means extending through the top of the conning tower for raising and lowering the gun, a platform adapted to be raised and lowered with said gun, means operable from said platform for training said gun, and means for supplying ammunition to the top of the conning tower, said gun having means associated therewith for neutralizing substantially all of the reaction due to firing a projectile from the gun, whereby the conning tower is not subjected to the greater part of the force of reaction of the gun. 45
- 50 8. The gun mounting for submarines, comprising the combination with the conning tower of a submarine, of a gun associated with the conning tower, a gun support rotatably mounted on said conning
- 55 tower, pneumatic means for raising and lowering said support, and a platform fixed to said support, said gun having means associated therewith for neutralizing substantially all of the reaction due to firing a projectile from the gun, whereby the conning tower is not subjected to the greater part of the force of reaction of the gun. 70
- 60 9. The gun mounting for submarines, comprising the combination with the conning tower of a submarine, of a non-recoil gun associated with the conning tower, a gun support rotatably mounted on said conning tower, means for raising and lowering said support, and a platform fixed to said support and having a plurality of openings for receiving ammunition when said support is lowered. 75
- 10 10. The gun mounting for submarines, comprising the combination with the conning tower of a submarine, of a gun associated with and arranged above the conning tower, means for raising and lowering said gun, and a spray shield extending well above the conning tower to form a fair-water for the gun when it is in its lowered position. 80
- 15 11. The gun mounting for submarines, comprising the combination with the conning tower of a submarine, of a gun associated with and arranged above the conning tower, means for raising and lowering said gun, a platform associated with said gun, and a spray shield extending well above the conning tower to form a fair-water for the gun when it is in its lowered position, and to form a shelter for said platform. 85
- 20 12. The gun mounting for submarines, comprising the combination with a watertight support extending well above the deck of the submarine, of an exposed gun mounted on said support, said gun having means associated therewith for neutralizing substantially all of the reaction due to firing a projectile from the gun, whereby said support is not subjected to the greater part of the force of reaction of the gun. 90
- 25 13. The gun mounting for submarines, comprising the combination with the conning tower of a submarine, of a gun arranged above the top of the conning tower, means for raising and lowering the gun, a platform adapted to be raised and lowered with said gun, means operable from said platform for training said gun, and means for supplying ammunition to the top of the conning tower, said gun having means associated therewith for neutralizing substantially all of the reaction due to firing a projectile from the gun, whereby the conning tower is not subjected to the greater part of the force of reaction of the gun. 95
- 30 14. The gun mounting for submarines, comprising the combination with a water- 100
- 35 15 120
- 40 16 125

tight support extending above the deck of the submarine, of an exposed non-recoil gun associated with said water-tight support, means for raising the gun above the top of said support and means for supplying ammunition to the top of said support.

15. The gun mounting for submarines, comprising the combination with a water-tight support extending well above the deck 10 of the submarine, of an exposed gun ar-

ranged above the top of said support, hoisting means associated with said support for raising and lowering the gun, means for hoisting ammunition to the top of said support, and a platform arranged above the top of said support and fixed with respect to the gun.

In testimony whereof I affix my signature.

LAWRENCE Y. SPEAR.
